UNITED STATES PATENT OFFICE.

CHARLES H. TOMLINSON, OF MANSFIELD, OHIO, ASSIGNOR TO THE TOMLINSON COUPLER COMPANY, OF MANSFIELD, OHIO, A CORPORATION OF OHIO.

HOLDING MECHANISM

Application filed May 4, 1925. Serial No. 27,711.

My invention relates to a holding mechanism and has particular reference to a device for holding a pivotally mounted car coupler in a substantially fixed position 5 when the coupler is not in use.

Car couplers used on electrically operated lines are usually pivotally mounted so that they have considerable lateral movement for the reason that electric cars are usually operated over tracks which have very short radius curves and if the couplers were not pivotally mounted great stress would be brought upon the coupler or the car body and damage most likely be done to the 15 equipment.

When two or more cars are coupled together it will be recognized that the front and rear coupler on the train will be free to move laterally about their pivotal points 20 when the train suddenly rounds a curve and this may be dangerous to life and property and at the same time annoyance to the passengers due to the bumping of the coupler against its stops as it swings from side to 25 side.

Therefore, I have produced an invention for preventing the lateral movement of the couplers whenever they are not in coupled relation.

30 My invention is so arranged that the couplers may be moved into locked position manually or they may be locked in a central position automatically upon the separating of two coupled cars. The locked 35 couplers will be released automatically upon two cars being coupled and the air for operating the air brakes completed from car to car through the fluid pressure lines.

My invention resides in the new and novel 40 construction, combination and relation of the various parts herein described and shown in the drawing accompanying this specification.

In the drawing: 45 Fig. 1 is a side view showing my invention as mounted underneath a car body and in locking engagement with a spring draw bar carrier used to yieldingly support a coupler head and permit its lateral movement at the same time.

A spring draw bar carrier similar to that shown in Fig. 1 is shown and described in my Patent No. 934,375, dated September 14, 1909, and this patent also shows the spring

carrier as mounted upon a circle bar and 55 supporting a pivotally mounted coupler. I have not described the spring carrier in detail for the reason that its construction is not a part of my invention herein described.

Fig. 2 is an end view in elevation of Fig. 60 1.

Fig. 3 is a longitudinal sectional view of my invention.

Fig. 4 is a top view of the holding member.

Fig. 5 is a side view of two cars, as in 65 Fig. 1, in coupled relation.

In mounting car couplers for lateral or radial movement they are generally pivotally secured to the car body and supported adjacent the extreme end of the car by what 70 is known as a spring carrier designated in the drawing as C. These carriers are secured to the under-sills 1 of the car body by means of hangers 2 to which is secured a circle bar 3. The carrier C is provided with 75 over-turned lugs 4 which rest upon the circle bar 3. There is a space between the inner ends of the lugs 4 and between these ends the hangers 2 are secured by means of the 80 bolts or rivets 5 and the hangers are secured to the sills 1 by means of the bolts 6. It will be understood by reference to my previous patent mentioned above that the circle bar is of sufficient length to take 85 care of the required lateral movement of the coupler. As just described, the spring carrier C is free to move laterally both when its coupler is connected with the coupler on another car or when it is uncoupled and the car swings around a curve, as already 90 described. The spring carrier also permits the coupler to move up and down with breaks in grade, as described in my previous patent.

In order to prevent the lateral movement 95 of the coupler when not in coupled relation, I employ an automatic device H arranged to normally engage the carrier C through the action of a spring and to maintain a released position with respect to the carrier 100 C through fluid pressure means.

Nearly all electric cars at the present day are equipped with the air brake system and when two cars are coupled together the fluid pressure conduits on the coupled cars are also coupled together, and I make use of this fact in releasing the couplers for lateral movement and maintaining them in 105

a released position when two cars are coupled together.

The holding device H comprises a cylinder 7 which is closed by a cap 8 at one end. 5 To the cap 8 is secured a boss 9 having a passage 10 therethrough and into the chamber 11 of the cylinder 7. The outer end of the passage 10 is screw-threaded, as shown at 12, and by means of which a hose 13 may 10 be connected to the holding device H for communication with the chamber 11. Mounted in the chamber 11 is a piston 14 provided with packing 15 to prevent air pressure from one side of the piston to the 15 other. Secured to the piston is a projecting piston rod 16 passing through the opening 17 in the end of the cylinder opposite the cap 8. The end of the cylinder through which the piston rod 16 passes forms a 20 shoulder 18 and interposed between this shoulder and the piston 14 is a spring 19 constantly urging the piston rod 16 and piston 14 toward the cap 8. The piston rod is secured to the piston head 14 by means of 25 the nut 20.

A friction holding member 21 is secured to the piston rod 16 by means of the bolts 22. It is evident that other means of securing these parts together may be employed. 30 The holding member 21 is provided with a face 23 which engages the face 24 on the movable carrier and is held against the movable carrier through the medium of the spring 19. The holding device H may be 35 mounted on the circle bar 3 by means of the foot 25 and the bolt and nut 26. The foot member 25 is of such a width as to not interfere with the movement of the carrier 3 and it is usual to mount the holding device 40 H central of the circle bar so that it will rest substantially upon the longitudinal center line of the car. With such mounting the coupler will be held in a substantially central position and if two cars are brought 45 together on a tangent or straight track, they will usually be centered so that no manual centering will be required, and if the uncoupling is done on the tangent or straight track then the holding device will 50 lock the coupler automatically in central position when the cars are separated.

The fluid-pressure connection between two cars usually comprises a pipe 27 which may be connected to the face of the coupler as 55 at 27', as shown in my Patent No. 1,094,612, dated April 28, 1914, whereby the fluid pressure connection between two cars may be made automatically or the fluid pressure connection between the cars may be made 60 by a hose coupling as is common in steam road operation. To the fluid pressure line 27 I connect the hose 13 and I interpose a valve 29 between such connection and the source of fluid pressure supply on the car 65 and this valve 29 must always be closed when

a car is operating as a unit, but must always be open between two cars when they are coupled together especially if the line 27 is part of the air brake system, but the front and rear valves on a train of two or 70 more cars must remain closed when the cars are coupled.

From this it will be apparent that whenever the valve 29 is closed no air can flow into the fluid pressure connection 27 and 75 hence no air can be supplied to the cylinder 7 through the hose 13 and the spring 19 will maintain the holding member 20 in a lock-engaging position, that is, in a position to engage or be engaged by the carrier C. If, however, the two cars are coupled together and the valves 29 between the coupler cars are open, either on one car or both if both are supplied with a complete air system, then the fluid pressure connection 27 between the two cars will be flooded with air pressure and the air will flow through the hose 13 into the cylinder 7 and the piston 14 will be moved against the action of the spring 19 and the holding member 21 will 80 be moved out of engagement with the carrier C or out of an engaging position therewith. If now the valves 29 are closed the holding member 21 will remain disengaged due to the trapped air pressure between the 85 valves 29 and will remain so until the air pressure is reduced sufficiently either by leakage, separation of the coupler heads or bleeding as by the valves 29 when closed.

This will permit free lateral movement of 100 the two carriers C and the cooperating couplers 28 and this free movement will continue as long as the cars are coupled, the valve 29 open on one or both of the coupled cars, and sufficient air pressure is in the conduit 27 between the valves 29 on the two cars. The holding devices H on the uncoupled ends of the train will remain in engagement with the carrier C because the conduit 105 27 will have no pressure therein as the valve 29 will be closed, which is necessary when the air brake system on the two cars is in operative condition.

It will be possible for one to manually move the coupler and its carrier into locking engagement with the holding member 21 as the holding member is held by the yielding spring 19 and when the coupler is moved into alignment with the holding device H the carrier will first engage the beveled faces 30 and with sufficient force applied to the coupler the member 21 will be moved back as the coupler advances until the coupler has been brought into its proper position. 115

It will be quite evident that the holding device H may be suspended upon a plate or other form of support mounted between the sills 1-1 in place of mounting it upon the circle bar 3, and its position with respect 120

to the sides of the cars may be anything desired within range of the lateral movement of the coupler, but the usual position is in line with the center longitudinal line of the 5 car.

It will also be apparent that in place of having the friction member 21 hold the carrier in position by friction only that the member 21 may be so arranged as to actually 10 interlock with the carrier C, as for instance, by placing a small projection 31 upon the engaging face 23 of the member 21 which will engage with a corresponding recess in the engaging face 24 of the carrier C. Also, 15 it will be evident that the member 21 might be projected downward a sufficient distance so as to interlock with lugs upon the coupler stem 28.

The member 21 may be secured to the rod 20 16 by set screws or other means which will permit the adjustment of the member 21 relative to the rod 16 both rotatably and longitudinally and this will no doubt be of 25 advantage under conditions where the operating mechanism may be supplied for use with parts already installed.

Many other modifications will suggest 30 themselves, but which will fall within the scope of my invention and, therefore, I wish 35 to be limited only by my claims.

I claim:

1. The combination with a radially movable coupler, of means operating to prevent the radial movement of the coupler when 35 not in coupled relation with a companion coupler and operating to permit unlimited movement of the coupler when in coupled relation.

2. The combination with a radially movable coupler, of means to prevent the radial movement of the coupler when not in coupled relation and to permit free radial movement of the coupler when the coupler is in 40 coupled and operating relation with a companion coupler.

3. The combination with a radially movable car and air coupler, of spring-held means interlocked with the coupler to prevent the radial movement of the coupler 45 when not in coupled relation but automatically released from said interlock when air is flowing to said coupler.

4. The combination with a laterally movable coupler, of means to hold the coupler 50 in a predetermined position and to prevent lateral movement when not in coupled relation and pneumatic operated means to release the holding means when the coupler is in operative coupled relation with a companion coupler.

5. The combination with a laterally movable coupler, of means to hold the coupler 55 in a predetermined position and against lateral movement when not in coupled relation and means to automatically release the 60

holding means and maintain it out of operative relation with the coupler when the coupler is in operative relation with a companion coupler.

6. The combination with a pair of co- 70 operating radially movable car couplers on two cars, of holding means on each car for said couplers arranged to automatically release the couplers and permit unlimited and free radial movement when the cars are operating coupled and to automatically limit and prevent the free radial movement of the couplers on their respective cars when the couplers are moved apart.

7. The combination of a radially movable car coupler mounted on a car, a fluid-pressure system, means to connect the fluid-pressure system on two coupled cars and valves to control the fluid pressure from car 80 to car and holding means to prevent the radial movement of the couplers when the cars are operating singly and to permit the radial movement of the coupled couplers when the cars are cooperating, the said means 85 comprising a holding member operated by the fluid-pressure to a non-holding position when the fluid-pressure controlling valves on one or both cars are open and means to move the holding means to a holding position 90 when the said valve or valves are closed and to maintain the said holding means in a holding position when the cars are separated.

8. The combination with a car coupler 100 mounted on a car for radial movement and having a carrier for the coupler mounted on the car for radial movement, of holding means to engage the carrier when the car is operating singly to prevent the radial movement of the coupler and means to release the said holding means from engagement with the carrier when the car is operating with its coupler connected to a companion coupler.

9. In a coupler holding device to permit 110 or prevent the lateral swing of a car coupler, depending upon the coupler being coupled to or uncoupled from a cooperating coupler respectively, comprising in combination a cylinder, a piston mounted therein and movable in one direction by a spring and in the other direction by a fluid-pressure and means operated by the movement of the piston by the spring to prevent the lateral 115 swing of the coupler and to permit the lateral swing of the coupler when the piston is operated by the fluid pressure.

10. The combination with a support bar 120 secured to a car adjacent its end, of a carrier slidably mounted thereon to move in a lateral direction, means on the carrier to support a pivotally mounted car coupler, a fluid pressure system on the car and means 125 normally engaging the carrier when the 130

- coupler is uncoupled to prevent lateral movement of the carrier and operated from the fluid pressure system to permit free lateral movement of the carrier when the coupler is coupled to a co-operating coupler.
11. The combination with a car provided with a fluid pressure system of a pivotally mounted car and fluid pressure coupler to cooperate with a similar car and fluid 10 coupler, a valve to control the flow of air to the fluid pressure coupler, a carrier to support the coupler, holding means operated automatically to prevent the free lateral movement of the coupler when uncoupled 15 and operated automatically from the fluid pressure system when the control valve is open and the coupler in coupled relation with a cooperating device to permit the free operation of the holding means and means connecting the holding means to the fluid pressure 20 system.
12. The combination with a car and air coupling mechanism, of means normally holding the coupler in a fixed and predetermined position, but automatically releasing the same when the coupler is in operating relation with a cooperating coupler.
13. A coupler holding device comprising a cylinder, a piston mounted in the cylinder, means to move the piston in one direction and means to move the piston in the other direction and means operated by the piston and adjustable relative to the piston to prevent the radial movement of the coupler when the piston moves in one direction and to permit the radial movement of the coupler when the piston moves in the other direction. 25 30 35

In testimony whereof I affix my signature.

CHARLES H. TOMLINSON.
